CLAIM

I claim the ornamental design for the spinal fusion cage, as shown and described.

DESCRIPTION

FIG. 1 is a top, front perspective view of a spinal fusion cage according to an embodiment of the disclosure.

FIG. 2 is a top view of the spinal fusion cage.

FIG. 3 is a bottom view of the spinal fusion cage

FIG. 4 is a right side view of the spinal fusion cage.

FIG. 5 is a left side view of the spinal fusion cage.

FIG. 6 is a front view of the spinal fusion cage.

FIG. 7 is a rear view of the spinal fusion cage; and,

FIG. 8 is a rear perspective view of the spinal fusion cage. The portions shown in dashed lines form no part of the claimed design.
